PISTON PUMP

Kenneth R. Lung, Dayton, Ohio, assignor to The Tait Manufacturing Company, Dayton, Ohio, a corporation of Ohio

Application June 6, 1955, Serial No. 36,385

Term of patent 7 years

(Cl. D65—1)

FIG-1

FIG-2

FIG-3

FIG-4

Fig. 1 is a perspective view of the piston pump embodying the invention;

Fig. 2 is a side elevational view of the piston pump of Fig. 1;

Fig. 3 is an end elevational view looking from right to left in Fig. 2; and

Fig. 4 is an elevational view of the opposite side of the pump from the side shown in Fig. 2.

The design is characterized by the features illustrated in full lines in the drawing.

I claim:

The ornamental design for a piston pump, substantially as shown and described.
